Merle D. McNamee, San Gabriel, Calif., assignor to McNamee Coach Corporation, South El Monte, Calif.,
a corporation of California

Filed Nov. 9, 1959, Ser. No. 58,289

Term of patent 14 years

(Cl. D14—3)

Fig. 1 is a front perspective view of a camp coach for pick-up trucks or similar article, showing my new design;

Fig. 2 is a front perspective view of a fragmentary portion thereof taken from the opposite side of Fig. 1;

Fig. 3 is a front elevational view thereof;

Fig. 4 is a fragmentary top plan view thereof; and

Fig. 5 is a fragmentary side elevational view thereof.

The essential features of the design are shown in solid lines in the drawing.

The pick-up truck shown in broken lines is for purposes of illustration only.

I claim:

The ornamental design for a camp coach for pick-up trucks, or similar article, substantially as shown and described.
